United States Patent Office

Des. 211,393

Patented June 11, 1968

211,393

PORTABLE LANTERN

William H. Doring, Old Greenwich, Conn., David O. Chase, Camillus, N.Y., and William W. Sammons, Pittsfield, Mass., assignors to Union Carbide Corporation, a corporation of New York

Filed June 28, 1967, Ser. No. 7,631

Term of patent 14 years

(Cl. D48—24)

FIG.1.

FIG.2.

FIG.3.

FIG.4.

FIG.5.

FIG. 1 is an isometric view of the portable lantern;
 FIG. 2 is a top view of the lantern shown in FIG. 1;
 FIG. 3 is a side view thereof;
 FIG. 4 is a bottom view; and
 FIG. 5 is a rear view.
 The dominant features of our design reside in the portions shown in full lines.

We claim:

The ornamental design for a portable lantern, as shown and described.
